UNITED STATES PATENT OFFICE

150,489

DESIGN FOR A PANEL TOY

Rubert C. Bockus, Gardner, Mass., assignor to
Gem Crib & Cradle Company, Gardner, Mass.,
a corporation of Massachusetts

Application August 22, 1946, Serial No. 132,725

Term of patent 14 years

(Cl. D34—15)

To all whom it may concern:

Be it known that Rubert C. Bockus, a citizen of the United States, residing at Gardner, in the county of Worcester and State of Massachusetts, have invented a new, original, and ornamental Design for Panel Toy, of which the following is a specification, reference being had to the accompanying drawing, forming part thereof.

Fig. 1 is a view in elevation; and

Fig. 2 is a top edge view of a panel toy showing my new design.

I claim:

The ornamental design for a panel toy, as shown.

RUBERT C. BOCKUS.
